 In Germany August 4, 1931

13 Claims. (Cl. 204—31)

The present invention relates to improvements in and apparatus for working up gases containing hydrocarbons in electric arcs.

It is already known that deposits of carbon on the electrodes and on the walls of the reaction chambers cause great difficulty in the conversion of gases containing hydrocarbons in electric arcs. In order to prevent this objection various precautions have been suggested such as diluting the hydrocarbons to be worked up, for example with hydrogen, protecting the electrodes by surrounding them with a gas poorer in carbon, or adding substances to the gas which consume carbon, such as oxygen or steam.

15 We have now found that even highly concentrated hydrocarbons or gases entirely consisting of hydrocarbons can be treated in electric arcs and in particular converted into final gases rich in acetylene in a simple manner without the 20 said precautions and while avoiding the deposition of carbon to a great extent, by causing the striking points of the electric arcs to rapidly move on the surfaces of both electrodes. By imparting to the striking points a rapid movement 25 the deposition of carbon black in the electric arcs and on the electrodes is prevented to a far-reaching extent, so that gases containing large amounts of carbon in the unit of space, as for 30 example highly concentrated propane, can be worked up in a manner free from objection even without any dilution and without special addition of protective gas at the electrodes. The speed of movement of the striking points of the arcs is selected great enough to prevent any great local 35 heating, for example up to about 400° C., in the neighbourhood thereof. The velocity of the striking points as a rule should be greater than 5 centimeters per second and preferably greater than 20 centimeters per second. The striking 40 point is the place at which the electric current issues from the electrode into the gas space. Any substances which conduct the electric current and preferably those which have a satisfactory thermal stability such as copper, iron or graphite 45 may be used for the construction of the electrodes. Besides gaseous and vaporous hydrocarbons which are especially suitable initial materials for the process according to the present 50 invention liquid hydrocarbons suspended in the form of mists in carrier gases, such as hydrogen, or brown-coal dust may be treated in the described manner. The process according to the present invention is, of course, not restricted to 55 highly concentrated hydrocarbons or gases con-

sisting entirely of hydrocarbons, but also less concentrated hydrocarbons, for example those containing substantial amounts of an inert gas, such as nitrogen or hydrogen as for example coke oven gas may be employed as initial materials. 5 The said gaseous and vaporous and suspended liquid hydrocarbons are hereinafter referred to as "vaporized hydrocarbons".

Natural gas, coal gas, gases arising from the low temperature carbonization of coals or lignites, waste gases from the destructive hydrogenation of coals, tars and mineral oils or other gases comprising suitable vaporized hydrocarbons may be employed as initial materials.

In particular with gases rich in hydrocarbons, especially those of higher molecular weight than methane, a rapid movement of the striking points should be set up. In these cases the velocity of these striking points is preferably not lower than 20 centimeters per second while with gases containing substantial amounts of inert gases, such as coke oven gas also lower velocities, as for example between 5 and 20 centimeters per second, may be employed.

The surface of the electrodes which is played upon by the striking points of the arcs should not be selected too small. The most suitable size of the said surface depends on the heat conducting properties and the cooling action of the flowing gases. This size must be the greater the smaller is the capacity of conducting heat and the smaller is the cooling action of the flowing gases. The movement of the striking points of the arcs may be effected, for example by electromagnetic means, or mechanically, as for example by means of a stream of gas; in the latter case the gas to be treated or other gases such as nitrogen or hydrogen may be employed for this purpose. The electrodes are preferably constructed in the form of tubes. If the speed of movement of the striking point of the arcs is great enough any previous deposition of carbon black on the electrodes disappears entirely and the formation of carbon black in the electric arc itself ceases almost entirely. When the said speed of movement is sufficiently great electrodes composed for example of carbon or graphite even diminish in size.

The nature of this invention will be further described with reference to the accompanying drawing which illustrates diagrammatically an electric arc reaction chamber suitable for carrying out the process according to this invention, but the invention is not restricted to the particular arrangement shown.

L is the electric arc, E the electrode, J the in- 55

sulation, G_1 and G_2 the gas inlets, F the tube which is connected to the earth and in which the electric arc burns, A is the gas outlet and S the voltage supply.

5 A part of the gas to be treated is tangentially introduced at G_1 into the cylindrical space B and then, while in a rotary movement, passed through the hollow space of the electrode E to the electric arc L . By the said rotary movement of the gas 10 introduced at G_2 a rapid movement is imparted to the striking points of the arc. Because of its tangential introduction into the system the gas has a whirling motion as it passes through the arc. By varying the amount of gas introduced at 15 G_2 it is possible to increase the voltage consumption of the electric arc within wide limits, as for example up to 50 per cent. The curve in the electrode E (shown in dotted lines) indicates how the electrode burns after use for long periods of 20 time. The gas supplied at G_1 is tangentially introduced into the cylindrical space C .

In order to operate electric arc reaction chambers, in which it is desired to prevent the growing of the electrode in the sense of the present 25 invention, alternating current or rectified alternating current is especially suitable because after the temporary suspension of the discharge on the electrode the electric arc strikes again from a different place on the electrode.

30 The electric arc reaction chamber of the type hereinbefore described has the great advantage that in the working up of carbonaceous substances, such as the preparation of acetylene, the deposition of carbon black in the electric arcs and 35 on the electrodes is so far prevented by moving the striking points of the arcs that gases containing large amounts of carbon per cubic meter, as for example propane, can be worked up in a manner free from objection even without any dilution and without special addition of protective 40 gas at the electrodes. If gases not participating in the reaction are supplied in order to cause the movement of the striking points of the electric arc they may act also as protective gases. But 45 it is a great advantage of the present invention that this dilution is not necessary and that consequently the energy efficiency is very good.

The following example will further illustrate the nature of this invention but the invention is 50 not restricted to this example.

Example

80 cubic meters per hour of a 95 per cent propane are worked up in an electric arc reaction 55 chamber the voltage-conducting electrode of which consists of a stick of graphite, the energy consumption of the arc being 100 kilowatts. 100 cubic meters of a gas mixture containing between 60 from 8 to 9 per cent of acetylene and about 3 kilograms of carbon black are obtained per hour. The energy yield is from 80 to 90 liters of acetylene per kilowatt-hour. The reaction chamber must be shut off after a short time by reason of 65 short circuit caused by the carbon deposited on the electrode.

If the stick-shaped electrode be replaced by a hollow electrode as shown in the accompanying drawing and a part of the gas to be treated which may vary between 1 to 15 per cent be led there- 70 through, whereby the striking point of the arc is set in rapid movement, so that it rotates about 100 times per minute, the energy consumption of the arc rises from 100 to 120 kilowatts. The final gas contains from 14 to 16 per cent of acetylene. 75 The energy yield amounts to from 120 to 130

liters of acetylene per kilowatt-hour. After several hours the operation is still free from objection. The electrode carries no deposits and the content of carbon black in the gas is scarcely noticeable.

What we claim is:

1. In the production of acetylene by treatment of a gaseous hydrocarbon in the electric arc the step of continuously causing the striking points of the electric arc to rapidly move on the surfaces of both electrodes to or from different points on each electrode. 10

2. In the production of acetylene by treatment of a gaseous hydrocarbon in the electric arc set up by an alternating current the step of continuously causing the striking points of the electric arc to rapidly move on the surfaces of both electrodes to or from different points on each electrode. 15

3. In the production of acetylene by treatment of a gaseous hydrocarbon in the electric arc set up by a rectified alternating current the step of continuously causing the striking points of the electric arc to rapidly move on the surfaces of both electrodes to or from different points on each electrode. 20

4. In the production of acetylene by treatment of a vaporized hydrocarbon in an electric arc set up between hollow electrodes the step of causing the striking points of the electric arc to rapidly move on the surfaces of both electrodes. 30

5. In the production of acetylene by treatment of a gaseous hydrocarbon in the electric arc set up by an alternating current between hollow electrodes the step of causing the striking points of the electric arc to rapidly move on the surfaces of both electrodes. 35

6. In the production of acetylene by treatment of a gaseous hydrocarbon in the electric arc set up by rectified alternating current between hollow electrodes the step of causing the striking points of the electric arc to rapidly move on the surfaces of both electrodes. 40

7. In the production of acetylene by treatment of a vaporized hydrocarbon in an electric arc set up between hollow electrodes the step of causing the striking points of the electric arc to move on the surfaces of both electrodes with a velocity of more than 5 centimeters per second. 45

8. In the production of acetylene by treatment of a vaporized hydrocarbon in an electric arc set up between hollow electrodes the step of causing the striking points of the electric arc to move on the surfaces of both electrodes with a velocity of more than 20 centimeters per second. 50

9. In the production of acetylene by treatment of a vaporized hydrocarbon in an electric arc set up between hollow electrodes, the step of causing the striking points of the electric arc to rapidly move on the surfaces of both electrodes by tangentially introducing the gas into one of the hollow electrodes, thereby causing the gas to traverse the 55 arc in a whirling motion.

10. In the production of acetylene by treatment of a gaseous hydrocarbon in the electric arc set up by an alternating current between hollow electrodes, the step of causing the striking points of the electric arc to rapidly move on the surfaces of both electrodes by tangentially introducing the gas into one of the hollow electrodes, thereby causing the gas to traverse the 60 arc in a whirling motion. 65

11. In the production of acetylene by treatment of a gaseous hydrocarbon in the electric arc set up by a rectified alternating current be- 70

tween hollow electrodes, the step of causing the striking points of the electric arc to rapidly move on the surfaces of both electrodes by tangentially introducing the gas into one of the hollow electrodes, thereby causing the gas to traverse the arc in a whirling motion.

12. In the production of acetylene by treatment of a vaporized hydrocarbon in an electric arc set up between hollow electrodes, the step of causing the striking points of the electric arcs to rapidly move on the surfaces of both electrodes by passing a whirling stream of gas through the electrodes.

13. In the production of acetylene by treatment of a vaporized hydrocarbon in an electric arc set up between hollow electrodes, the step of causing the striking points of the electric arc to rapidly move on the surfaces of both electrodes by passing part of the vaporized hydrocarbons in the form of a whirling stream through the electrodes. 5
